COCKPIT ENCLOSURE AND RELEASE
MECHANISM

Theodore Ulmer, North Hollywood, and Charles E. Sowle, Van Nuys, Calif., assignors to Lockheed Aircraft Corporation, Burbank, Calif.

Application October 13, 1941, Serial No. 414,748

8 Claims. (Cl. 244—121)

This invention relates to an improved transparent enclosure or canopy for airplane cockpits and the like, with special reference to the provision of a plurality of means for normal entrance and emergency exit therefrom.

In a copending application, filed by Allan M. McConnell and William E. Braham, Serial No. 424,640 dated December 27, 1941, is disclosed a cockpit enclosure of double paned construction especially designed to resist the bursting stresses imposed by pressurizing or supercharging the cockpit for high altitude flights. The present invention relates to the provision of a convenient access hatch in the sealed enclosure, and the further provision of escape means for either abandoning the airplane in flight, or to enable the pilot to escape in the event the airplane turns over upon landing, thus preventing the use of the normal entrance and exit arrangement.

It is accordingly an object of this invention to provide a cockpit enclosure or shell that is normally hinged along one edge and releasably locked along the opposite edge, to be opened in the manner of a door or hinged hatch, inside and outside latch releasing means being provided for the operation of the normal latch.

It is a further object of this invention to provide a cockpit enclosure or shell of the type described wherein the shell is hinged along one edge or side for normal access to the cockpit, and wherein the hinged side may also be released at will to permit bodily removal of the shell or closure when desired.

It is another object of this invention to provide a closure or shell of the type described that is normally operated as a hinged access door or hatch, but that can be released on the latch and hinge edges simultaneously to allow the closure to blow or fall off to permit the pilot to abandon an airplane in flight should occasion so require, it being evident that a hinged closure could not be manually opened, and held open during exit, while the airplane was in flight at present day speeds.

It is also an object of this invention to provide an improved auxiliary escape hatch that can be opened should the closure as a whole be jammed or restrained from opening, as in the case of a top closure held shut by overturning of the airplane.

Other and further important objects of this invention will be apparent from the disclosures in the specification and the accompanying drawings.

This invention in its preferred form is illus-

trated in the drawings and hereinafter more fully described.

As illustrated on the drawings—

Figure I is a fragmentary perspective view of an airplane control nacelle embodying a transparent closure or hood having the features of this invention.

Figure II is an enlarged transverse section through the closure or hood taken on the line II—II of Figure I.

Figure III is an enlarged detail of the escape hatch latch shown in Figure II, showing one of the quick release catches in side elevation.

Figure IV is an inside plan view of Figure III.

Figure V is a section on the line V—V of Figure IV showing the quick release mechanism.

Figure VI is a schematic diagram of the control linkages for the latch and hinge sides of the closure or hatch.

As shown—

We have chosen to illustrate our invention as applied to a transparent closure, canopy, or hood for a pilot's cockpit; the particular arrangement shown comprising a control nacelle or fuselage 10 supported from wings 11, a pilot's cockpit having a forward windshield 12 and a transparent closure or shell 13 to give side and vertical vision. For the purposes of this invention the closure or shell 13 need not be transparent, nor of double paned construction, these features being embraced in a previously mentioned co-pending application.

For the purpose of this invention the removable or hinged shell 13, together with its normally attached escape hatch 14, is mounted in a frame 15 forming part of the structure of the control nacelle 10. One longitudinal edge of the shell 13 comprises a glass retaining frame 16 hinged at 17 to a secondary frame 18 normally locked to the nacelle frame 15 by a series of hooks 19 pivoted at 20 in the frame 15 and engaging pins 21 carried by the secondary frame 18. For convenience in further description, the hinged side of the shell 13 will be referred to as the right side, using the conventional forward looking terminology. This would place the hinge on the far side of Figure I and the left side of Figure II.

The opposite edge of the shell 13 is formed as a glass engaging post 22 which cooperates with a similar post 23 bordering the upper edge of the escape hatch 14, as will be described in more detail hereinafter. The lower longitudinal edge of the escape hatch 14 is provided with a frame 24 similar to the frame 18 without the hinge, a second set of hooks 19, pivoted as before, engaging

pins 21 in the frame 24. This second set of hooks 19 will be referred to as the left side in what follows.

The posts 22 and 23, between the closure 13 and the escape hatch 14, are normally locked together so that the members 13 and 14 operate as a unitary structure. This is accomplished by providing a cover plate 25, on the post 23, which has a hooked lip 26 engaging in a groove in the post 22; a quick release retainer being provided on the inside to lock the two posts together. The retainer is shown in Figures III, IV and V wherein a pair of spaced links 27 are pinned to a bracket 28 secured to the post 22, the links carrying a dog 29 at their free ends, which dog has a lug 30 engaging in a hook 31 on a bracket secured to the post 23. The dog 29 is arranged to operate on the toggle principle but does not pass over center, so that the arrangement is unstable and is normally held in position by a pin 32. Several of these retainers are positioned along the length of the joint between the posts 22 and 23 and the corresponding pins 32 are connected by wires 33 to enable the pins to be pulled simultaneously to release all the retainers by a single motion, since pulling the pins releases the unstable toggle arrangements to open by their own pressure or by pressure acting on the escape hatch.

For normal access to the cockpit the closure 13 and escape hatch 14 are unlatched along the left side; this being the near side in Figure VI showing the operating linkage. When so released the closure and hatch open upwardly about the hinge 17 on the right side. In order to operate the several hooks 19 on the left side in unison the hooks can be conveniently linked by a continuous cable 34 operating over front and rear pulleys 35 and 36 respectively. An outside handle 37 is provided to operate the front pulley 35, and an inside handwheel 38 is provided for the pilot's use. The right side hooks are similarly operated by an endless cable 39, only the rear pulley 40 being shown in Figure VI. For the right side, only an inside handwheel would be required, as it would be used only in emergency by the pilot, except during overhaul periods.

In an emergency, in flight, that required the pilot to bail out, the hooks on both sides would be released to allow the entire closure 13 and escape hatch 14 to be blown off by interior pressure, or thrust off by the pilot, as the pilot would be hampered in escaping if he had to hold the hinged closure open while climbing out.

In order to provide for simultaneous operation of the hooks on both sides, while permitting independent operation of the hooks on the left side for normal access, the rear pulleys on both sides are interconnected in such a way that the right side pulley 40 can operate the left side pulley 36, but not vice versa. A mechanism for making such a connection is shown in Figure VI, where the pulley 36 moves with a crank 41 linked at 42 to a cranked connecting shaft 43 similarly linked at 44 to a crank 45 free to rotate relative to the pulley 40. The pulley 40 carries a dog 46 engaging the crank 45 when the pulley 40 rotates clockwise in Figure VI, from the latched position shown. With this arrangement, normal operation of the left side hooks causes the crank 45 to move away from the dog 46 on the pulley 40; while emergency operation of the right side hooks causes the dog 46 to drive the left side pulley 36 to simultaneously release both sides of the combined closure 13 and escape hatch 14.

While we have described this invention in connection with a pilot's transparent canopy or hood, it will be evident that the combined access and emergency provisions of our closure can equally well be used at other locations, as in connection with gun turrets or blisters, passenger compartments, or the like, and for marine or automotive installations.

It will thus be seen that we have invented an improved access and emergency arrangement wherein a normally hinged closure can in an emergency, or for service, be completely and simultaneously released from its frame, and in which a portion of the closure can be opened independently of the main closure to serve as an escape hatch.

Having thus described our invention and the present preferred embodiments thereof, we desire to emphasize the fact that many modifications may be resorted to in a manner limited only by a just interpretation of the following claims.

We claim:

1. In an airplane a closure forming a combined access and escape hatch comprising in combination with a receiving frame and a closure frame, means for hingedly connecting said frames together along one side thereof, means for latching said frames together along another side thereof, releasing means for said latching means, secondary releasing means so constructed and arranged as to release the hinged connecting means from its frame, means including one of the latch edges of the closure and so constructed and arranged as to form a removable section normally rigid with said closure, and means for disconnecting said section from said closure for opening movement independent thereof.

2. In an airplane a closure forming a combined access and escape hatch including a receiving frame therefor, means for hingedly connecting said closure to the frame for pivotal movement relative thereto, the escape hatch being formed in said closure adjacent one edge thereof, emergency release means for rigidly connecting said escape hatch portion to the remainder of the closure whereby it normally forms part of the same, and latching means releasably engaging said escape hatch with the receiving frame whereby to normally control the opening movement of said closure and hatch as a unit.

3. In an airplane a closure forming a combined access and escape hatch including a receiving frame therefor, means for hingedly connecting said closure to the frame for pivotal movement relative thereto, the escape hatch being formed in said closure adjacent one edge thereof, means for rigidly connecting said escape hatch portion to the remainder of the closure whereby it normally forms part of the same, emergency release means associated with said rigid connecting means, and latching means releasably engaging said escape hatch whereby to normally control the opening movement of said closure and hatch as a unit.

4. In an airplane a closure forming a combined access and escape hatch including a receiving frame therefor, means for hingedly connecting said closure to the frame for pivotal movement relative thereto, releasable mounting means for said hinged means, the escape hatch being formed in said closure adjacent one edge thereof, emergency release means for rigidly connecting said escape hatch portion to the re-

mainder of the closure whereby it normally forms part of the same, and latching means releasably engaging said escape hatch whereby to normally control the opening movement of said closure and hatch as a unit.

5. In an airplane a closure forming a combined access and escape hatch including a receiving frame therefor, means for hingedly connecting said closure to the frame for pivotal movement relative thereto, releasable mounting means for said hinged means, the escape hatch being formed in said closure adjacent one edge thereof, emergency release means for rigidly connecting said escape hatch portion to the remainder of the closure whereby it normally forms part of the same, latching means releasably engaging said escape hatch whereby to normally control the opening movement of said closure and hatch as a unit, and means for simultaneously releasing said hinge means and said latch means whereby to facilitate complete release of said closure.

6. In an airplane a closure forming a combined access and escape hatch including a receiving frame therefor, a hinged connection between one side of said closure and the frame, the escape hatch being formed in said closure along its opposite or free edge, and means for releasably securing the closure and the escape hatch portion thereof together to operate as a unit.

7. In an airplane a closure forming a combined access and escape hatch including a receiving frame therefor, a hinged connection between one side of said closure and the frame, an escape hatch forming a portion of said closure along its opposite or free edge, means for releasably securing the two portions of the closure together to operate as a unit, said releasable securing means including an unstable toggle connection, lock for said toggle connection, and emergency release means for said lock whereby to release said escape hatch portion from the other portion of the closure.
